FIG. 5

INVENTOR.
W.E. CUMMINS.

B. Craig,
ATTORNEY.

UNITED STATES PATENT OFFICE

WALTER E. CUMMINS, OF LONG BEACH, CALIFORNIA

PUMPING JACK

Application filed January 7, 1931. Serial No. 507,172.

This invention relates to improvements in pump jacks.

The general object of the invention is to provide an improved long stroke pumping jack.

Another object of the invention is to provide an improved pumping jack wherein the sucker rod is actuated by endless chains.

An additional object of my invention is to provide a pumping jack operated by endless chains wherein the chains are operated in a novel manner.

Other objects and advantages of this invention will be apparent from the following description taken in connection with the accompanying drawings wherein:

Fig. 1 is a side elevation of my improved pump jack.

Fig. 2 is an end elevation of the pump jack.

Fig. 3 is a horizontal section taken on line 3-3 of Fig. 1.

Fig. 4 is a horizontal section taken on line 4-4 of Fig. 1.

Fig. 5 is a vertical section taken on line 25 5-5 of Fig. 1.

Fig. 6 is an enlarged side elevation of a portion of the endless chain showing the means for connecting the pitman thereto.

Fig. 7 is a section taken on line 7-7 of Fig. 30 6, and

Fig. 8 is a top plan view of the parts shown in Fig. 7.

Referring to the drawings by reference characters I have indicated my improved pump jack generally at 10. As shown the pump jack 10 includes a supporting frame 11 which is adapted to be mounted on the derrick floor adjacent the well casing 12 from which a pump actuating sucker rod 13 ex-

40 tends. Directly over the sucker rod 13, I provide a cross head 14 having tongues 15 thereon which are positioned in guides 16 secured to the frame 11. The sucker rod 13 may be removably connected to the under side

45 of the cross head 14 in any suitable manner such as indicated by the connection 17.

Pivottally connected to the upper portion of the cross head as at 18, I provide a pitman 19 which is secured to an endless chain drive means 20 by a connector 21. The chain drive

20 comprises a pair of spaced endless chains 22 which are mounted on spaced lower sprockets 23 and spaced upper sprockets 24. Each of the chains 22 are made up of a plurality of pairs of links 25 which are secured together by pins 26.

To secure the connector 21 in position between the chains 22 a pair of links 25 of each chain 22 are removed and the inner links of the chain positioned in slots 27 provided in the connector and the outer links are positioned adjacent the outer ends of the connector. Pins 28 are then positioned in the pin apertures of the links and in recesses 29 provided in the connector and are secured in position by pins 30. Intermediate the length of the connector 21, I provide a reduced portion 31 which is cylindrical and on which the upper end of the pitman 19 is mounted to rotate.

The lower sprockets 23 are each mounted on a shaft 33 and each of which is journaled in a bearing 34 mounted on the frame 11. The upper sprockets 24 are each mounted on a shaft 35 each of which is journaled in a bearing 36 mounted on the frame 11. The bearings 36 are preferably provided with a plurality of shaft apertures 36' so that the shafts 35 may be positioned different distances from the shafts 33 to vary the length of the chains 22 and thereby change the length of the stroke of the pitman 19.

Secured to the outer ends of the shafts 33, I provide sprockets 37 which are connected by endless chains 38 to sprockets 39 which are secured to a drive shaft 40 of a speed reduction transmission 41 which may include gears to allow the speed to be varied. The transmission 41 may be of any desired type and is shown as driven by a shaft 42 from an electric motor 43 but any other suitable driving means may be used if desired.

For counteracting the weight of the suspended parts and that of the fluid elevated by the pump I may provide a plurality of weighted members 45 which are removably positioned on a table 46 which in in a down position rests on a plate 47 mounted on the frame 11. Secured to the table 46 and extending upwardly therefrom I provide a pair

55

60

65

70

75

80

85

90

95

100

of hollow tubes 48 and secured to the plate 47 and extending upwardly therefrom I provide a pair of rods 49 which are positioned in the tubes 48 and act as guides for the table 46.

Connected to the upper ends of the tubes 48 as at 50, I provide cables 51 which are positioned over pulleys 52 and connected as at 53 to arms 54 provided on the cross head

14. The pulleys 52 are mounted on a shaft 55 which is journaled in a bearing 56 mounted on the frame 11.

The sucker rod 13 when the device 10 is not operating is preferably raised with the counter weight table in a lowered position as shown in Fig. 1.

When the motor 43 is started it rotates the lower sprocket 23 of the chain drive device 20 through the medium of the transmission 41, the sprockets 39, the chains 38 and the sprockets 37. As the sprockets 23 rotate they cause the chains 22 to travel over the sprockets 24. As the chains 22 travel they move the pitman 19 downward which through the medium of the cross head 14 allows the sucker rod 13 to move downward and as the cross head 14 moves downward it raises the counter weights 45 through the medium of the cables 51.

30 When the pitman 19 reaches the limit of its downward travel as shown in Fig. 5 and the chains 22 continue their travel they move the pitman upward which through the medium of the cross head 14 moves the sucker rod 13 upward on a fluid elevating stroke and the counter weights 45 move downward with the weight thereof assisting to elevate the fluid.

When the pitman 19 reaches the limit of 40 its upward travel the chains 22 move it downward again as previously described and this upward and downward travel of the pitman continues as long as the motor 43 is operating.

Any length of pumping stroke desired may 45 be obtained by altering the distance between the sprockets 23 and 24 and by providing for the corresponding raising or lowering of the counter weights 45.

From the foregoing description it will be 50 apparent that I have provided a novel long stroke pump jack which is simple in construction and highly efficient in use.

Having thus described my invention, I claim:

55 1. For use with a well casing having a sucker rod therein, a pump jack, said pump jack including a supporting frame, a cross head, spaced guides on said frame in which said cross head actuates, means to connect said sucker rod to said cross head, means to reciprocate said sucker rod, a movable table, a plurality of weighted members on said table, a plurality of spaced, upwardly extending tubes secured to said table, a plate on said frame, a plurality of spaced, upwardly ex-

tending rods secured to said plate, said rods being positioned in said tubes, a plurality of pulleys mounted on said frame, a cable supported by each of said pulleys, one end of each of said cables being secured to one of said tubes and the opposite end being secured to said cross head whereby when said cross head is in a lowered position said table is in a raised position and vice versa.

2. For use with a well casing having a sucker rod therein, a pump jack, said pump jack including a supporting frame, a cross head, spaced guides on said frame in which said cross head actuates, means to connect said sucker rod to said cross head, a pair of spaced endless chains, each of said chains being mounted on a lower sprocket and an upper sprocket, a connecting member secured to said chains, a pitman, one end of said pitman being pivotally connected to said cross head and the opposite end of said pitman being pivotally connected to said chain connecting member, said upper sprockets being mounted on shafts journaled in bearings on said frame, said lower sprockets being mounted on shafts journaled in bearings on said frame, drive sprockets secured to said last mentioned shafts, a speed reduction transmission, means to drive said transmission, means to drive said drive sprockets from said transmission, a weighted member, a plate on said frame, means on said plate to guide said member and means to connect said member to said sucker rod.

3. A pump jack including a supporting frame, a cross head, spaced guides on said frame in which said cross head actuates, a sucker rod, means to connect said sucker rod to said cross head, a pair of spaced endless chains, each of said chains being mounted on a lower sprocket and an upper sprocket, a connecting member secured to said chains, a pitman, one end of said pitman being connected to said cross head and the opposite end of said pitman being connected to said chain connecting member, said upper sprockets being mounted on shafts on said frame, said lower sprockets being mounted on shafts on said frame, drive sprockets secured to said last mentioned shafts, a speed reduction transmission, means to drive said drive sprockets from said transmission, a movable table, a plurality of weighted members on said table, a plurality of spaced, upwardly extending tubes secured to said table, a plate on said frame, a plurality of spaced, upwardly ex-

jack including a supporting frame, a cross head, spaced guides on said frame in which said cross head actuates, means to connect said sucker rod to said cross head, a pair of spaced endless chains, each of said chains being mounted on a lower sprocket and an upper sprocket, a connecting member secured to said chains, a pitman, one end of said pitman being pivotally connected to said cross head
10 and the opposite end of said pitman being pivotally connected to said chain connecting member, said upper sprockets being mounted on shafts journaled in bearings on said frame, said lower sprockets being mounted on shafts
15 journaled in bearings on said frame, drive sprockets secured to said last mentioned shafts, a speed reduction transmission, means to drive said transmission and means to drive said drive sprockets from said transmission,
20 a movable table, a plurality of weighted members on said table, a plurality of spaced, upwardly extending tubes secured to said table, a plate on said frame, a plurality of spaced, upwardly extending rods secured to said
25 plate, said rods being positioned in said tubes, a plurality of pulleys mounted on said frame, a cable supported by each of said pulleys, one end of each of said cables being secured to one of said tubes and the opposite end being se-
30 cured to said cross head whereby when said cross head is in a lowered position said table is in a raised position and vice versa.

In testimony whereof, I hereunto affix my signature.

35 WALTER E. CUMMINS.
